GLENN D. ANGLE, OF CINCINNATI, OHIO, ASSIGNOR TO THE LE BLOND AIRCRAFT ENGINE CORPORATION, OF CINCINNATI, OHIO, A CORPORATION OF OHIO

CYLINDER FOR INTERNAL COMBUSTION ENGINES

Application filed August 11, 1930. Serial No. 474,466.

This invention pertains to internal combustion engines and relates more particularly to the method of providing a compression tight joint, between the cylinder or barrel 5 constructed of one metal, say steel or cast iron, and a head portion constructed of a dissimilar metal, as aluminum, which has a higher coefficient of expansion.

Owing to the high expansion of the aluminum the practice heretofore has been to screw the aluminum head to the barrel or cylinder section with a shrink fit, heating the head before screwing it in place on the barrel portion. Other methods such as bolting the two 15 parts together have been employed.

In the use of either of the above methods the practice has been, to machine a separate ring and shrink this ring around the aluminum head portion where it joined the steel 20 or cast iron cylinder or barrel after it was shrunk in place.

This required the making of an extra part and an extra assembly operation to complete the cylinder assembly.

The principal object of my invention is to provide a compression tight joint between the cylinder and head with facility and cheapness and yet insure an air tight fit. My invention eliminates the conventional 25 ring, which is unsatisfactory and obviates the necessity of heating the head for assemblage.

A particular embodiment of my invention is selected for illustration in the accompanying drawing, in which

Figure 1 is a vertical elevation, part section, of an internal combustion engine cylinder embodying my invention.

Figure 2 is an enlargement of part of the section shown in Figure 1.

Referring now to the drawing, the cast iron or steel barrel 1 has at its upper end a flange portion 2, this flange portion being machined in the form of a female portion or groove 3, having a flat bottom and straight sides 4. The machining of this groove leaves an external integral flange or retaining member 5, the use of which will be apparent later.

A head 6, made of aluminum or aluminum alloy, which has a higher coefficient of ex-

pansion than the steel or cast iron barrel 1, has machined on its bottom edge a male portion or projection 7 having a flat lower portion and straight sides 8.

A series of studs 9, are screwed into the 55 projecting male portion 7, and have a threaded end for the reception of a nut 11. The flange 2, in the bottom of the groove or female portion 3, has a series of holes 10, coinciding with the studs of the head portion 5. 60

To assemble the structures above described, the studs 9, in the aluminum head portion are entered in the holes 10 of the flange portion 2 and the nuts applied. As these nuts are tightened the male portion of head 6, is 65 forced with a light fit into the female portion of the barrel, the result being a compression tight joint where the surface 4 of the groove 3 meet the same surfaces 8 on the projecting portion 7 of the aluminum head 6. 70

In addition to the joints formed by the surfaces 4, there is formed another joint at 12.

Looking now at the drawing it will be seen that when the aluminum head portion 6 has been tightly clamped to the barrel 1, the flange 5 heretofore mentioned, completely surrounds the outer portion of projection 7 and being a part of the steel or cast iron barrel, prevents, when the aluminum head becomes hot, any expansion beyond that of the steel or cast iron 75 barrel 1 and since the coefficient of expansion of the aluminum head portion 6 is much greater than that of the steel or cast iron barrel 1, it follows that the joint formed by the junction of the male portion of the aluminum head 80 and the female portion of the steel or cast iron barrel, becomes tighter as the head expands under the heat generated by the operation of the engine. Since all expansion of the head 85 away from the joint between the head and the wall 4 of groove 3 at the side next the bore of the cylinder is resisted by the integral flange or retaining member 5 and the studs 9 being of a material with less expansion than the aluminum head portion 6, they will 90 resist the expansion away from the bottom of the groove 3, of that part of the projecting or male portion 7 that seats on the flat part 95 of the female or groove portion 3.

The integral flange or retaining member 5 100

further operates to prevent growth of the projecting portion 7, of the head 6 as it ages.

It is thus seen that the integral flange or retaining member 5, obviates the use of a separate structure to resist the expansion of the head portion 6 where it joints the barrel member 1.

While the invention has been described above in its preferred form, it will be obvious that various changes and modifications may be made therein without departing from the spirit or scope thereof, and it is therefore desired that only such limitations may be imposed thereon as are necessitated by the prior art or specifically set forth in the appended claims.

I claim as my invention and desire to secure by Letters Patent of the United States:

1. In combination, a cylinder with a laterally extending flange and a flange extending from the laterally extending flange toward the end of the cylinder, and a head to fit on said end of the cylinder, having an annular flange fitting inside the second mentioned flange of the cylinder, the two interfitting flange structures being of materials of different coefficients of expansion whereby the flanges of the head and cylinder draw more tightly together radially upon increased heating of the parts.

2. In combination, a cylinder with an annular axially opening groove with axially parallel sides and a bottom at right angles to the sides, and a head to fit on said cylinder, having an annular axially extended flange with axially parallel sides and a bottom at right angles to its sides, said flange being proportioned relatively to the cylinder groove to fit snugly in the groove, and the grooved structure of the cylinder having a lower coefficient of expansion than the flanged structure of the head whereby the flange expands against at least one side of said groove upon increased heating of the parts.

3. In combination, a cylinder with a radially separated substantially axially extending flange, and a head with a substantially axially extended flange to fit inside the cylinder flange, the cylinder structure adjacent to and inward from its flange and the end of the head flange being substantially parallel, and fastening means connecting these parallel portions of the cylinder and head, said cylinder and said fastening means having a lower coefficient of expansion than said head whereby the head flange expands radially outward against the cylinder flange and expands axially against said cylinder structure adjacent to and inward from the cylinder flange by virtue of the less expansion of said fastening means.

4. In combination, a cylinder with an annular axially opening groove with axially parallel sides and a bottom at right angles to the sides, a head to fit on said cylinder, hav-

ing an annular axially extended flange of cross sectional shape and size relative to the cross sectional shape and size of the cylinder groove to fit snugly in the groove, and fastening means connecting the bottom of the groove and the end of the head flange, the grooved structure of the cylinder and said fastening means having a lower coefficient of expansion than the flanged structure of the head whereby the head flange expands against at least one side of the cylinder groove and its end expands against the bottom of the groove by virtue of the less expansion of the fastening means.
